UNITED STATES PATENT OFFICE.

EDWARD ALBERT JONES, OF FIUME, AUSTRIA-HUNGARY.

MULTIPLE-CYLINDER ENGINE.

SPECIFICATION forming part of Letters Patent No. 768,460, dated August 23, 1904.

Application filed January 12, 1904. Serial No. 188,710. (No model.)

To all whom it may concern:

Be it known that I, EDWARD ALBERT JONES, a citizen of England, residing at Fiume, Austria-Hungary, have invented certain new and useful Improvements in Multiple-Cylinder Engines, of which the following is a specification, reference being had therein to the accompanying drawings.

This invention has for its object improvements in multiple-cylinder engines in which the connecting-rods of several cylinders act upon one crank-pin, these improvements relating more particularly to the connection of the oscillating piston-rods with the piston and the common crank-pin.

The invention is illustrated in the accompanying drawings, in which—

Figure 1 shows a piston-rod adapted to oscillate and constructed in accordance with this invention, together with crank-pin and piston, in partial vertical section. Fig. 2 is a cross-section on the line A B of Fig. 1, in which the positions of the (four, for example) oscillating piston-rods acting upon the crank-pin are shown. Fig. 3 is a partial horizontal section on the line C D of Fig. 1. Fig. 4 is a side elevation of the crank-disk as viewed from the left-hand side of Figs. 1 and 3. Fig. 5 represents the piston separately by means of a section on the line E F of Fig. 1. Figs. 6, 7 and 8, 9 illustrate two details, respectively.

The piston-rods *a* are connected with the piston *b* by means of a cylinder-joint, which is constituted on the one hand by the cylindrical boss *c* on the upper face of the piston and on the other hand by a narrow plate *d*, curved in accordance with the surface of the boss *c* and forming the foot of the piston-rod *a*, with which it forms one piece. This foot-plate *d* is seized on its two narrow lateral edges, curved in accordance with the cylinder-face, by two pins *f f*, which are half cut away toward the cylinder-face, these pins being introduced into holes drilled in the piston-wall and secured in position by means of the packing-ring *h*, which is placed in the usual manner in a groove on the outer side of the piston, this groove being cut also in the pins *f f*, extending to the outer face of the piston.

The connection of the oscillating piston-rods *a* with the crank-pin *k* is effected by the provision on both sides of this pin upon each of the two crank-disks *i* of an annular protuberance *m*, concentric with the crank-pin *k*. These two annular protuberances *m* constitute a slideway into which the lateral edges of plates *n*, curved in accordance with the radius of the crank-pin *k* and forming the heads of the piston-rods *a*, extend, the width of these plates being calculated in such a manner that the head-plates *n*, Fig. 2, corresponding to the various piston-rods *a a a a*, do not impede each other on the rotation of the crank.

In order to permit of the introduction of the head-plates *n* of the separate piston-rods *a* into the slideway running on both sides of the pin, the protuberances *m*, constituting this slideway, are each recessed at *q* in such a manner that the start and finish of the recesses in the two annular protuberances *m* each fall in the same generatrix. When the head-plates *n* of all the piston-rods *a* have been introduced into the slideway, the two recesses *q* are closed by means of pins *p*, one of which is let into each of the crank-disks, which pins (see Figs. 2 and 3 and 6 to 9) are partially cut away, so as to correspond with the annular groove, and are held in position owing to the fact that their head *r*, bent at right angles, is let into a corresponding recess formed on the outer side of the crank-disks *i*, Fig. 3, by means of a screw-bolt *t*, passing through the crank-pin *k* and the disks *i*, and of which the head *s* is let into the head *r* of the left-hand pin *p*, while its end is screwed into the head *r* of the right-hand pin *p*. The two pins *p p* are connected one with the other and with the crank, so that it is impossible for any loosening to occur even with the highest speeds. In order to further secure the pins *p* against rotation or loosening, there is also arranged upon the outer side of each crank-disk a screw *v*, the head of which extends partly within the head *r* of the respective pin *p*.

In order to better distribute the pressure exerted on the crank-pin *k* by the different piston-rods *a*, a sleeve *w* is mounted on the crank-pin *k* in the usual manner, and as the

crank-pin *k* is rigidly connected on both sides with the crank-disks *i*; this sleeve is made in two parts.

I claim—

- 5 1. In multiple-cylinder engines, in which a number of connecting - rods act on a single crank-pin the connection of the connecting-rod heads with the crank-pin, consisting of an annular slideway running on both sides of the pin and concentric therewith and recessed for the admission of the rod-heads, and in which the connecting-rod heads are guided and means for closing the slideway, substantially as described.
- 10 2. In multiple-cylinder engines, in which a number of connecting - rods act on a single crank-pin the connection of the oscillating piston-rods with the piston, consisting of the provision of a cylinder-joint, consisting of a cylindrical boss upon the outer side of the piston and a plate forming the foot of the connecting-rods or piston - rods and concentric with the surface of the boss, which plate is seized by pins let into the cylinder-wall and suitably cut away substantially as described.
- 15 3. In multiple-cylinder engines, a plurality of connecting - rods having heads, a single

crank-pin therefor, a connection for the rod-heads and crank-pin consisting of an annular slideway running on both sides of the pin and concentric therewith and recessed for the admission of the rod-heads, and in which the rod-heads are guided, and detachable pins fixed in the crank-disks and having heads for closing the recesses formed in the slideway.

30 4. In multiple-cylinder engines, a plurality of connecting - rods having heads, a single crank-pin therefor, a connection between the said heads and crank-pin comprising an annular slideway running on both sides of the said pin and concentric therewith and recessed for the admission of the rod-heads and in which the said heads are guided, detachable pins carried by the crank-disks having heads for closing the recesses in said slideway, said heads of the 35 pins being rectangularly bent, and a screw-bolt common to said heads and passed through the crank-pin and the crank-disks.

40 In testimony whereof I hereunto affix my signature in presence of two witnesses.

EDWARD ALBERT JONES.
